[57] CLAIM

The ornamental design for a transmission shifter console, as shown and described.

DESCRIPTION

FIG. 1 is a right rear elevated perspective view of a transmission shifter console showing my new design, the broken line showing a portion of the console that is not considered part of the claimed design.

FIG. 2 is a reduced left front elevated perspective view of the transmission shifter console design of FIG. 1;

FIG. 3 is a reduced plan view thereof;

FIG. 4 is a reduced left side elevational view thereof;

FIG. 5 is a reduced rear elevational view thereof;

FIG. 6 is a reduced right side elevational view thereof; and,

FIG. 7 is a reduced front elevational view thereof.
The bottom of the transmission shifter console is plain and unornamental and is therefore not shown.
